ENVELOPE

Carl G. Miehlke, Chicago, Ill.

Application November 4, 1937, Serial No. 172,688

3 Claims. (Cl. 229—82)

This invention is concerned with a safety envelope provided with sealing means which are broken or damaged if an attempt is made to open the envelope, thus furnishing a safeguard against unauthorized opening or tampering with the article and its contents.

The sealing means comprises an insert of thin tissue paper marginally secured inside the stationary or fixed sealing flap and providing an auxiliary pocket therein, and a tongue cut out from the material of the fixed flap which may be brought into sealing engagement with the movable sealing flap and with the material of the auxiliary pocket, respectively, in a variety of ways, upon closure of the envelope. Any attempt to open the envelope tends to break or damage either the sealing tongue or the material of the auxiliary sealing pocket, or both. The envelope is thus protected in an effective manner, against the danger of unauthorized opening, which may be important in case of valuable contents, and safer transit is assured by its use.

The new envelope is described below with reference to the drawing, wherein

Figs. 1 and 2 are a plane view and a side view, respectively, of the new envelope;

Fig. 3 is a transversely enlarged partial section along line 3—3 of the envelope showing the various component parts;

Fig. 4 is an enlarged section along line 4—4 through the movable sealing flap of the envelope; and

Fig. 5 is a partial transverse section through the closed and sealed structure with the movable flap in sealed position;

Fig. 6 shows a section similar to the one indicated in Fig. 5, but illustrates a different manner of using the sealing means;

Fig. 7 shows another way of using the envelope, namely, with the raised portion of the movable sealing flap in alignment with and within the aperture in the fixed flap and in sealing engagement with the tissue paper within the pocket; and

Fig. 8 illustrates a further way of using the envelope, and specifically the tongue cut out from the fixed sealing flap to secure the envelope against unauthorized opening.

Like parts are numbered alike throughout the drawing.

The envelope consists of the usual pocket portion comprising the stationary or fixed sealing flap 11 and a movable sealing flap 12. The latter is marginally provided with adhesive, as indicated in Fig. 1 at 12'. Inside of the envelope pocket,

and particularly inside the stationary sealing flap 11, is disposed a sheet of thin tissue paper 20 which is only marginally secured to the pocket portion of the envelope body, as shown in Fig. 1 in shaded lines, indicating adhesive thus providing an auxiliary pocket 21. Cut out or punched out from the body of the stationary or fixed flap 11 is a tongue 13 which carries at least one, and if desired, two rows of perforations 14 and 15. This tongue 13 may be provided with adhesive, as indicated by the shading thereon. The fixed sealing flap 11 is also provided with a slot 17 substantially along the line of the tongue 13 as shown in Fig. 1. This tongue 13 may be bent out from the body of the envelope, as shown in Figs. 2 and 3, and when thus pulled out it opens up an elongated aperture 22 which is closed on its back side by the sheet material 20 forming the auxiliary pocket 21. Attention is particularly called to the fact that this material 20 is only marginally attached inside the envelope.

Another slot 16 is provided in the movable flap 12 for receiving the tongue 13 in a manner to be subsequently described, when it is desired to seal the envelope. The material of the flap 12 is recessed so as to form a depression 18 and, conversely, a raised portion 19, as indicated in Figs. 1, 2, and 4. This particular feature is not critical and may even be dispensed with without seriously affecting the invention. The depression 18 receives and accommodates the tongue 13 in a certain embodiment of the invention indicated in Fig. 6, and the raised portion 19 which may be provided with adhesive, as indicated in Fig. 1 by the shading, enters into the aperture 22 in the embodiment shown in Figs. 6, 7 and 8, as will be subsequently described in detail.

The tongue 13 and the material 20 of the auxiliary pocket constitute additional sealing means which are brought into engagement with the movable flap 12 when the envelope is to be sealed.

One manner of sealing this new envelope is illustrated in Fig. 5 which is a partial transversely enlarged section through the closed and sealed structure with the movable flap 12 in sealed position. The various parts are shown on an enlarged scale and also somewhat distorted as to proportions so as to bring out the details. Numeral 11 is the body of the stationary flap which carries the tongue 13 provided with the perforations 14 and 15, and 20 is the material marginally attached inside the envelope substantially edge-wise of the fixed flap 11, and forming the auxiliary pocket. The tongue 13 may be gummed on the inner surface where it engages the tissue pa-

per 20, and the movable flap 12 may be marginally gummed as already mentioned. The method of sealing conforms, in this example, entirely to the usual sealing method of orthodox envelopes.

5 The tongue 13 may be disregarded except that its inside may be wetted so as to attach it firmly to the tissue paper 20. When the movable flap 12 is closed against the fixed flap 11, as shown, and is sealed thereto, it will also attach in sealing engagement with a portion of the tongue 13, and this tongue is thus brought into sealing engagement with the tissue paper 20 as well as with the movable flap 12. The slots or perforations 16 and 17 perform no particular function in this 10 manner of using the envelope except that they increase the hazards attending an unauthorized attempt to open the envelope.

Assuming that the envelope is tampered with by any of the known means, for example, by applying steam or solvents and prying open the 20 movable flap 12, a point will be reached where the manipulation will affect the juncture of the tongue 13 where it is firmly sealed to the fragile tissue paper 20 and also to the movable flap 12.

25 Such an attempt, no matter how it may be executed, is very likely to result in damaging or tearing either the tongue 13 at its perforated portions or the tissue paper 20, or both.

Fig. 6 shows a section similar to the one shown 30 in Fig. 5, but illustrates a different manner of making use of the new sealing means. The tongue 13 is in this case threaded through the slot 16 of the movable flap 12 and nestles within the depression 18 while the raised portion 19 engages the tissue paper 20. The perforations 15 are in this case substantially along the line of the slot 16. The tongue 13 internally provided with adhesive attaches firmly to the movable flap 12, while the usual portion of this movable flap 40 which is also provided with adhesive engages the tissue paper 20, inasmuch as it enters into the aperture 22, as shown. The movable flap 12 may be provided with adhesive along the raised portion 19, as already stated before, but its usual 45 gummed section will be sufficient for most cases. Anyone attempting to tamper with the envelope would have to first remove the tongue 13 from its engagement with the flap 12. It is clear that this would cause considerable difficulties and 50 would most likely result in a tearing of the tongue 13, particularly at its perforations 14 or 15. Assuming, however, that the attempt to loosen the tongue 13 is successful, it would still be necessary to remove the flap 12 from sealing engagement 55 with the fixed flap 11 and also with the tissue paper body 20 which is quite fragile and easily damaged and torn. It stands to reason, therefore, that an envelope sealed in this manner and provided with these additional sealing means would 60 not be tampered with. At any rate, any attempt to tamper with it would leave its marks and would put the addressee on his guard, thus giving him means for seeking redress and taking appropriate steps against a recurrence.

65 In Fig. 7, the movable flap 12 is first attached in the usual way, after threading the tongue 13 through the slot 16. The movable flap is thus in sealing engagement with the fixed flap 11 and through the aperture 22 also with the tissue paper 20. The tongue 13, which in this case may be 70 gummed externally, is then bent downwardly and attached in sealing engagement with the edge of the movable flap 12 as well as with the body of the fixed flap 11. Tampering or unauthorized 75 opening would again require first loosening and

removal of the tongue 13 which would be attended by hazards due to the slot 17 and to the perforations 14 and 15. It would then be necessary, as in the former case, to loosen and remove the movable flap 12 from engagement with the fixed flap 11 and with the tissue paper 20, respectively. The difficulties in the way of such an attempt are apparent, and it would certainly leave its mark and furnish means toward exposure of anyone attempting such tampering. 10

In Fig. 8 is shown a further way of using the new envelope and securing its contents against unauthorized opening. The tongue 13 is again threaded through the slot 16 in the movable flap 12 prior to sealing this flap in engagement with the fixed flap 12 and with the tissue paper 20, as previously described. The tongue 13 is next bent downwardly as in Fig. 7, but is also threaded through the slot 17 in the fixed flap 11, entering into the auxiliary pocket 21. The tongue 13 may be externally gummed, as previously described, and after sealing the various parts together, as shown in Fig. 8, the envelope is quite secure against tampering, so far as provisions can reasonably be made to safeguard against such an attempt. In this example, the removal of the tongue 13 by unauthorized means appears well nigh impossible, without breaking either the tissue paper seal 20 or the tongue 13 itself, or the fixed flap 11, because it would be necessary to withdraw the end of the tongue from the pocket 21 (to which it is sealed) and then to lift it off the body 11 and the end of the movable flap 12, incurring the danger of breaking the perforations 14 or 15, and finally, to remove the movable flap 12 from sealing engagement with the body 11 and also with the fragile tissue paper body 20. 15 20 25 30 35

The envelope may in other respects conform to the orthodox manner of making and using it. 40 It may be made of paper or any other suitable material. The depressed and raised portions 18 and 19, respectively, may be provided where the thickness of the material requires it. Special gumming of the area denoted by the raised portion 19 may be provided where required. In most cases the usual marginal gumming of the flap 12 will suffice because it will be within reach of the aperture 22 in the fixed flap and will thus reach the insert 20 for the purpose described. 45 50

Changes may be made within the scope and spirit of the appended claims wherein I have defined what I believe is new and what I desire to have protected by Letters Patent of the United States. 55

I claim:

1. In an envelope having a fixed sealing flap forming a pocket and a movable sealing flap for sealing engagement with said fixed sealing flap to close said pocket, safety seal means, comprising a tongue in said fixed sealing flap normally closing an aperture therein, a slot in said movable sealing flap for threading said tongue therethrough incident to sealing said envelope and thereby exposing said aperture, a sheet of tissue paper or the like secured marginally within in said pocket against the inside of said fixed sealing flap, and a raised area on the inside of said movable sealing flap for sealing engagement with said tissue paper through said exposed aperture in said fixed sealing flap. 60 65 70

2. In an envelope, a tongue cut out from the material forming the pocket of the envelope and exposing upon removal thereof an aperture in the back portion of said pocket, a sheet of tissue pa- 75

- per marginally secured within said pocket against said back portion and loosely extending within said pocket across said aperture, a slot in the sealing flap of said envelope for threading said tongue therethrough incident to closing said envelope to expose said aperture, and a raised area projecting from the inside plane of said sealing flap for alignment with and within said exposed aperture when said flap is in sealing position, said raised portion engaging said tissue paper within said pocket in sealing engagement therewith, and said tongue engaging the outside of the back of the sealed envelope in sealing engagement therewith.
- 5 3. In an envelope, a tongue cut out from the material of the back portion thereof which forms the pocket therefor and being normally disposed within an aperture therein, a sheet of tissue pa-
- per or the like marginally secured within said pocket against said back portion and normally loosely extending within said pocket across said tongue and said aperture, and safety seal means in the sealing flap of said envelope, comprising a slot for threading said tongue therethrough incident to moving said sealing flap into closing position and thereby exposing said aperture, a raised area projecting from the inside plane of said sealing flap for alignment with and within said exposed aperture when said flap is in marginal sealing engagement with said back portion, said raised portion engaging said tissue paper within said pocket in sealing engagement therewith, and a depressed area in said sealing flap on the outside thereof for receiving said tongue in sealing engagement therewith.
- 10 15
